US0D1089920S

(12) **United States Design Patent** (10) **Patent No.:** **US D1,089,920 S**
(45) **Date of Patent:** **** Aug. 19, 2025**

(54) **MOP**

(71) Applicant: **Yongkang Longjie Industry and Trade Co., Ltd.**, Zhejiang (CN)

(72) Inventor: **Meiqiao Ma**, Jiangsu (CN)

(**) Term: **15 Years**

(21) Appl. No.: **29/977,112**

(22) Filed: **Dec. 5, 2024**

(51) **LOC (15) Cl.** **07-05**

(52) **U.S. Cl.**

USPC **D32/50**

(58) **Field of Classification Search**

USPC D32/17, 21–22, 50–52, 45

CPC A47L 13/58; A47L 13/14

Primary Examiner — John R Yeh

(57) **CLAIM**

The ornamental design for a mop, as shown and described.

DESCRIPTION

FIG. 1 is a front, top and right-side perspective view of the mop showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof;

FIG. 8 is a back, bottom and left-side perspective view thereof;

FIG. 9 is another perspective view thereof shown in an exploded condition;

FIG. 10 is another perspective view thereof shown in an exploded condition;

FIG. 11 is another front view thereof shown in an exploded condition;

FIG. 12 is another perspective view thereof shown in an exploded condition;

FIG. 13 is an enlarged view, of circled portion 13, of FIG. 1, thereof; and,

FIG. 14 is an enlarged view, of circled portion 14, of FIG. 10, thereof.

The broken lines throughout the drawing figures depict portions of the mop that form no part of the claimed design.

The dot-dash broken lines depict the boundaries of the FIGS. 1, 10, 13 and 14 enlargement that forms no part of the claimed design.

1 Claim, 14 Drawing Sheets
